UNITED STATES PATENT OFFICE

132,791

DESIGN FOR AN ABDOMINAL SUPPORT

Henry J. Lunney, Los Angeles, Calif.

Application November 12, 1941, Serial No. 104,117

Term of patent 3½ years

To all whom it may concern:

Be it known that I, Henry J. Lunney, a citizen of the United States and residing at Los Angeles, in the county of Los Angeles, State of California, have invented a new, original, and ornamental Design for an Abdominal Support, of which the following is a specification, reference being had to the accompanying drawing, forming part thereof, in which:

Fig. 1 is a perspective view of an abdominal support as seen from the one side and the front thereof, showing my new design;

Fig. 2 is a similar view showing the other side and back thereof; and

Fig. 3 is a fragmentary detail view illustrating the front and the side strips.

I claim:

The ornamental design for an abdominal support, substantially as shown.

HENRY J. LUNNEY.
